COMBING MACHINE FOR TEXTILE FIBERS

John William Nasmith, Heaton Mersey,
Manchester, EnglandApplication September 19, 1941, Serial No. 411,836
In Great Britain June 26, 1941

4 Claims. (Cl. 19—121)

The invention relates to combing machines of the rectilinear type in which a nipper is employed consisting of upper and lower nipper jaws, and which nipper reciprocates, in the operation of the machine, to and from the detaching means for a combed fiber tuft. In such machines, as is known, the nipper during each stroke opens automatically during the feed and tuft detaching periods and closes tightly by spring pressure on its backward movement for the actual combing period, that is to say, when the needles of the combing cylinder of the machine are passing through the tuft of fibers held by the nipper. It is necessary from time to time when the machine is stopped to open the nipper jaws widely to permit access to feed rollers within the nipper, for cleaning or for other purposes. They can however only be opened by removal of the spring pressure, which requires some effort, and the method necessarily employed is inconvenient.

In some machines the spring pressure applied to the upper nipper jaw is continuous; in others the spring is "dead" during the tuft detaching period, and if the machine is stopped at that point the spring pressure is easily removed. This is not the case however when the nipper is closed and the spring pressure is in full application. In all cases it is necessary, when the nipper jaws have been opened, to prop the jaws open whilst attention is being given to the feed rollers within. This again is inconvenient, due to the compactness of the machine parts at that point and the proximity of the needles of the top comb to the fingers of the operator.

The object of the present invention is the provision of means whereby the nipper can be instantaneously opened widely without effort when the machine is stopped—even if closed and under spring pressure at the moment of such stoppage—and will be held in that open condition automatically until closed for restarting. To this end the invention consists, in a combing machine of the type defined, in a spring co-acting with the nipper jaw in such a manner that the continued backward movement of the nipper after the jaws have closed upon the tuft of fibers to be combed is accompanied by closing pressure applied to the upper nipper jaw, the other extremity of the spring being anchored upon manually releasable means. Thus the mere release by hand of the latter, which is most conveniently a pivoted latch, causes elimination of the spring effect and also causes bodily movement of the spring as a whole, to open the nipper jaw widely and to maintain it in that condition until restored to operative position.

In rectilinear combing machines of the well-known Nasmith type two forms of nipper movement are in use, which for my present purpose may be differentiated broadly as having, in one

form, the swinging nipper hinged on a point below the combining cylinder; the nipper, in the other form of machine, hinging upon a point situated above such combining cylinder. The application of this present invention to combing machines of both forms, for a full understanding of such invention, will now be described with reference to the drawing annexed, wherein—

Figure 1 is a side view of spring mechanism and accessories as applied to a combing machine in which the nipper swings upon a point below the combining cylinder. The nipper jaw in this figure is open, and Figure 2 is a side view of the same when the nipper jaw has closed upon the lower and closing pressure is about to be applied.

Figure 3 is a side view of spring mechanism and accessories as applied to the other form of Nasmith combing machine above referred to, whilst Figures 4 and 5 show details of certain parts, disassembled, to assist in the explanation hereinafter following of Figure 3.

Referring first to Figures 1 and 2, the upper nipper jaw is indicated at 3, being borne by the arm 4, and the lower nipper jaw at 5. The arm 4 carrying the upper nipper jaw 3 is pivoted at 6 as usual, and in operation the whole nipper reciprocates in known manner along the arcuate path x, reaching, on the backward stroke, the position indicated by the pivot 6 in broken lines. The feed rollers 7 within the nipper are also as usual, and the usual combing cylinder is indicated at 8. Upon the pin 9 borne by the arm 4 is pivoted the extremity of link 10 the upper extremity of which is pivoted upon pivot pin 11 carried by the lever 12 which itself pivots upon pin 13 fixed in the framing of the machine 14. At the upper extremity of the vertical arm of the lever 12 is fitted the swivel 15 which receives the threaded shank 16 of the tension spring 17. The other extremity of the said spring is anchored upon the pin 18 borne by the lever member 19 pivoted at 20 in the framing 14 at the front of machine, and on this pin 18 upon the lever 19 there is pivoted the catch 21 which engages normally a shoulder 22 formed in the machine framing as shown. The pivoted lever member 19 and its associated catch 21 form a latch. Also fixed in the machine framing is the tapped pin 23, which serves as holder for the adjustable stop member 24, which makes contact normally with the vertical arm of the lever 12. When the nipper is open during the tuft detaching period the said vertical arm of the lever 12 is held by the spring 17 against the stop 24.

The operation of the mechanism is as follows: In normal working, the nipper reciprocates along the arcuate path x, to and from the detaching rollers shown in Figure 1 at 25. On the backward movement of the nipper, the upper jaw 3 closes upon the lower jaw 5 about midway of

its path—see Figure 2. The lower extremity of the link 10 has followed this movement, its pivot point 9 following the arcuate path indicated at y. Thus, as the backward movement of the nipper continues, and the nipper closes, this link 10 pushes lever 12 round on its pivot 13 to the right as viewed in the drawing, being pushed away from stop 24, and tension of the spring 17 is thus transferred from the stop, in an increasing degree, to the upper nipper jaw during the rest of the nipper movement backwardly. When, the machine being stopped, it is necessary to open the nipper jaws widely, it is only necessary to exert manual pressure upon the projecting end of the lever 19 and lift the end of the catch 21 to release the same. The tension of the spring 17 is thus released and the said spring being also bodily moved over, the pivot point 18 moves upon the arc z. Lever 19 is pushed to the right, the upper nipper jaw 3 thus opening widely and remaining in that condition until the parts are again restored to operative position by re-arrangement of the catch 21.

One set of the mechanism is described, but it is duplicated at the other side of the combing machine head, as will be understood.

Describing now the modification illustrated in Figure 3 and its companion Figures 4 and 5, there is shown the lever 26 which is part of the comb operating mechanism of a machine head and is fixed upon an oscillated shaft to be oscillated about centre 27. See U. S. Patent No. 1,369,532, issued February 22, 1921, Figure 6 of the drawing thereto, in which lever 21 is oscillated by the shaft W and compresses the spring N5 on backward movement of the nipper N3 from detaching rollers D, d. In this present invention the lever 26 is as to its general functions equivalent to the lever 21 of the prior specification, but upon the said lever 26 there is pivoted at 29 the forked lever 28 having a downward extension as shown in which extension is formed the orifice 30 in which swivels the swivel member 15, through a hole in which passes the upper extremity of spring shank 16 the lower extremity of which is pivoted as shown upon the upper nipper jaw. The spring 17 is a compression spring, and in Figure 3 it is compressed, the nipper being thus in closed condition. The lower end of the lever 28 abuts against the lever 26 at point 31—see Figures 4 and 5—and is held in that position by means of the catch 21 hinging on the lever 26 and engaging as shown in Figure 3 upon the shoulder 22 of the lever 28. This lever and the catch 21 form a latch. In both showings a lever and a catch form the latch, release of which nullifies the spring effect and displaces the spring and the nipper jaw, as set forth in the claims now on file. Due to the position of swivel 15 the compressive effect of the spring 17 in the position shown in Figure 3 is exerted upon the right of pivot point 29.

The spring arrangement described follows the movement of the upper nipper jaw, spring compression being at its maximum in the closed condition of the nipper jaws and position of lever 26 as shown. When the machine is stopped catch 21 is raised by the operator pressing on the arm of lever 28, this permitting the raising of latch lever 28 around its pivot point 29 with consequent bodily displacement of the swivel 15 to the left as seen in broken lines in Figure 3. The spring is thus "dead" and the nipper open until the parts are restored to working position.

As in the first form described with reference to Figures 1 and 2, one set of mechanism is shown in Figure 3, but as will be understood this is duplicated on the other side of the combing head.

I claim:

1. In a textile combing machine having upper and lower nipper jaws, a spring adapted to apply closing force to the upper nipper jaw on backward movement of the nipper jaw pair in the operation of the machine, such spring being bodily displaceable, a normally locked and releasable latch member, and connecting means between the spring and a movable part of such latch member and between such spring and the upper nipper jaw, the movable part of the latch member, spring, and connections being movable together on release of the latch member, the resultant movement of the upper nipper jaw being an opening movement.

2. In a textile combing machine having upper and lower nipper jaws, a tension spring, a normally locked and releasable latch member, a connection between the spring and a movable part of such latch member, and further connections between the spring and the upper nipper jaw, such further connections having spring-extending movement with the nipper jaw pair on backward movement of the latter, the assembly being bodily displaceable on spring-release movement of the movable part of the latch member with resultant opening of the upper nipper jaw.

3. In a textile combing machine having upper and lower nipper jaws, a normally locked and releasable latch member, and a compressible spring fitted between a movable part of such latch member and the upper nipper jaw and compressed on backward movement of the nipper jaw pair, such spring being bodily displaceable with spring-release movement of the movable part of the latch member with resultant maintained opening of the upper nipper jaw.

4. In a textile combing machine as claimed in claim 3, a lever pivoted in the machine and forming part of the operating mechanism thereof and thus being stationary when the machine is stopped upon which operational lever the movable part of the releasable latch member with its borne spring connection is pivoted.

JOHN WILLIAM NASMITH.
